UNITED STATES PATENT OFFICE.

HAROLD EDWARDS, OF SCHENECTADY, NEW YORK, ASSIGNOR TO GENERAL ELECTRIC COMPANY, A CORPORATION OF NEW YORK.

SYSTEM OF ELECTRICAL DISTRIBUTION.

SPECIFICATION forming part of Letters Patent No. 712,050, dated October 28, 1902.

Application filed March 30, 1901. Serial No. 53,633. (No model.)

To all whom it may concern:

Be it known that I, HAROLD EDWARDS, a citizen of the United States, residing at Schenectady, county of Schenectady, State of New York, have invented certain new and useful Improvements in Systems of Electrical Distribution, (Case No. 2,077,) of which the following is a specification.

- In many cases it is exceedingly desirable that the external characteristic of boosters used in connection with electric circuits should be as straight as possible—in other words, that the boosting effect should vary as nearly as possible in proportion to the current flowing through the booster. In practice it has been found that even when the magnetic field of the booster is worked upon that portion of the saturation-curve below the knee the desired straightness of the characteristic curve is not attained, thereby resulting in unsatisfactory operation of the line or lines to which the booster may be connected. Thus if the boosting effect at full load is adjusted to the proper amount then due to the hump of greater or less extent in the characteristic curve the boosting effect at half-load is too great, while if, on the other hand, the adjustments are made properly for half-load then at full load the boosting effect is insufficient. I have discovered that the defect referred to may be remedied by impressing upon the field of the booster a supplementary auxiliary magnetomotive force which varies in a proportion different from the variation of current in the booster itself.
- The voltage of the ordinary series-wound booster is proportional to something less than the first power of its current or excitation, while its output is nearly proportional to the second power of the current or excitation. Since the power-input of the motor driving the booster is substantially the same as the power-output of the booster, the current of the driving-motor will be nearly proportional to the second power of the current of the booster. By making the excitation of the booster proportional to some quantity intermediate between the first and second powers of the booster-current the voltage of the booster may be made to rise at a rate faster than the rise of current in the booster, there-

by taking the curve out of the booster characteristic, or even causing it to bend upward.

Since, as has been seen, the current of the driving-motor varies approximately in proportion to the second power of the current in the booster, I may produce in the field of the booster a sultant magnetomotive force proportional to a quantity intermediate between the first and second powers of the booster-current by providing the booster-field with a supplementary winding and passing a greater or less proportion of the motor-current through said winding.

For a better understanding of my invention reference is to be had to the following description, taken in connection with the accompanying drawings, in which—

Figure 1 represents in diagram one embodiment of my invention, while Fig. 2 is a diagram explanatory thereof.

As to the scope of the invention, attention is directed more particularly to the claims appended hereto.

In the drawings, 1 represents, conventionally, any suitable source of current feeding supply-mains 2 and 3, to which translating devices 4 of any desired character are connected either directly or indirectly.

At 5 is represented a series-wound booster having its armature 6 and series field 7 connected in series with each other and with one of the mains 2 3—as, for example, the main 3. This booster is mechanically driven by a suitable motor—as, for example, the shunt-wound motor 8—in this case shown as connected with its armature on the same shaft with or a continuation of the shaft of the armature of the booster 5. The armature of the motor 8 is indicated at 9 and carries a commutator 10, upon which bear commutator-brushes in the usual manner. These commutator-brushes 11 and 12 are connected to the terminals of the shunt-field 13, current being supplied to the field and armature circuits through connections with the mains 2 3 at the points 14 and 15, as indicated.

Current instead of passing directly from the main 2 to the motor 8, as heretofore, is in this case caused to pass through the auxiliary winding 16 on the field-magnet of the booster 5. The amount of current in this auxiliary

winding may be adjusted in any suitable manner—as, for example, by varying its number of effective turns or by the employment of an adjusting-shunt or any other well-known 5 means.

With the arrangement of circuits indicated it will be seen that the field of the booster is acted upon by two magnetomotive forces, one of which varies in proportion to the current 10 in the booster and the other in proportion to the current supplied to the motor. The current in the booster if acting alone would not cause a sufficient increase in the field of the booster to prevent a drooping of 15 the characteristic curve as the load comes on, while if the auxiliary winding 16, fed with the motor-current, were to act alone it would cause the field of the booster to increase in such a manner as to give an upward bend to 20 the characteristic curve. Therefore by combining the effects of each in suitable proportions, to be determined by calculation and trial in each particular case, the characteristic curve of the booster may be given any desired shape—either straight, bending upward, 25 or a magnified drooping.

With the arrangement so far as above described it will be observed that when no current is passing through the booster-armature 30 there will nevertheless be an electromotive force produced thereby due to the combined effect of residual magnetism, as well as the magnetization due to the small current flowing through the coil 16 in circuit with the driving-motor 8. To neutralize this electromotive 35 force, I provide a constantly-excited differential winding 17, which, as a matter of convenience, may be excited by being connected in series with the field of the motor, as shown.

40 The interrelation of the effects produced by the various windings of the booster may, perhaps, be better understood by reference to Fig. 2, which represents in a general way the phenomena referred to. The various curves

45 shown indicate by their abscissæ certain values of current and by their ordinates corresponding values of electromotive force of the booster. The dotted curve 18 is the characteristic which would be produced by the series winding 7 of the booster acting alone.

The dotted curve 19 is the characteristic which would be produced by the winding 16, carrying the current of the driving-motor, while the horizontal line 20 indicates the de- 55 magnetizing effect of the coil 17. The combined effect of the coils 7 and 16 may be represented by combining their respective curves 18 and 19, which produces the resulting characteristic 21, which is substantially a straight

60 line. To make this line start from the origin, the demagnetizing-coil 17 is employed, which when no current is flowing in the distribution system counteracts the combined effect of residual magnetism and the magnetizing

65 effect of the coil 16, thereby making the electromotive force of the booster zero when the load is zero. The resulting characteristic of

the booster is therefore approximately, if not exactly, a straight line, as indicated at 22.

Although I have shown my invention as 70 embodied in a single arrangement of circuits, I do not wish to be limited to the precise arrangements shown, since various modifications of the same may be made without departing from the spirit of my invention. 75

What I claim as new, and desire to secure by Letters Patent of the United States, is—

1. The combination of a booster, and auxiliary means for straightening the external characteristic of said booster. 80

2. The combination of a motor-driven booster, and means for causing its field excitation to vary in a proportion greater than the proportion of variation of current in the booster-circuit. 85

3. The combination of a series-wound booster, a motor for driving the same, and a winding on said booster fed by current passing through said motor.

4. The combination of a booster, a motor 90 mechanically coupled thereto, and a winding on said booster in circuit with said motor.

5. The combination of a series-wound booster, a motor connected thereto, said motor having a field-winding in shunt with its 95 armature-circuit, and an auxiliary winding on said booster in circuit with said motor.

6. A motor-driven booster having a plurality of field-windings, one in series with the armature of the booster and another in series 100 with the motor.

7. A motor-driven booster having a plurality of field-windings, one in series with the armature of the booster and another carrying current flowing through said motor. 105

8. A motor-driven booster having a plurality of field-windings, one of which is in series with the armature of the booster, another in series with the driving-motor, and a third constantly excited from a suitable 110 source.

9. A motor-driven booster having a plurality of field-windings, one of which is in series with the armature of the booster, another in series with the driving-motor, and a third in series with the field-winding of said motor. 115

10. The combination with the armature of a booster, of a field-magnet, and means for exciting the field-magnet by the resultant of 120 three magnetomotive forces, one of which varies in proportion to current passing through the armature of the booster, another in a greater proportion, and a third of substantially constant value but acting inversely 125 with respect to the other magnetomotive forces.

In witness whereof I have hereunto set my hand this 29th day of March, 1901.

HAROLD EDWARDS.
